(57) **CLAIM**

The ornamental design for a gas valve assembly with electronic ignition, as shown.

DESCRIPTION

FIG. 1 is a top perspective view of a gas valve assembly with electronic ignition showing our new design;
FIG. 2 is a bottom perspective view thereof;
FIG. 3 is a front plan view thereof;
FIG. 4 is a top plan view thereof;
FIG. 5 is a bottom plan view thereof;
FIG. 6 is a rear plan view thereof;
FIG. 7 is a side elevation view thereof; and,
FIG. 8 is a side elevation view of the opposite side of FIG. 7.
